PULSATATOR

John A. Schmitt, Milwaukee, and Lloyd F. Bender, Waukesha, Wis., assignors to The Universal Milking Machine Company, Waukesha, Wis., a corporation of Wisconsin

Application April 23, 1941, Serial No. 389,928

12 Claims.

(Cl. 31—62)

This invention pertains to pneumatic pulsator mechanism for alternating fluid pressure control, and is especially adapted for control of admission and exhaustion of air to and from pneumatic pulsating teat cups of mechanical milking apparatus, but obviously is not limited thereto, but is applicable to other alternating fluid pressure purposes.

The pulsator unit is of the fluid pressure operated type, wherein a reciprocating piston actuates two valve mechanisms, one of which governs the admission of fluid under pressure to effect automatic alternation of the piston, and the other of which alternately connects each of at least two fluid pressure conduits with a source of fluid under pressure and with a vacuum or exhaust influence.

The object of the invention is to simplify the construction, as well as the means and mode of operation of pneumatic pulsating devices, whereby they may not only be economically manufactured and operated, but will be more efficient in use, automatic in operation, uniform in action, having relatively few operating parts, and unlikely to get out of repair.

A further object of the invention is to provide a pulsator of compact construction and of a relatively low flattened contour which may be readily assembled on a milk receiver top, or in other locations where the available space is limited.

A further object of the invention is to provide an improved piston construction, and to provide non-circular piston chambers and pistons.

A further object of the invention is to provide an improved valve operating mechanism by which the reciprocating motion of the actuating piston is transmitted to the control valve with a delayed action snap-over operation.

A further object of the invention is to provide improved timing means for the valve operating means.

A further object of the invention is to provide a pulsator unit having the advantageous structural features and inherent meritorious characteristics and mode of operation herein-mentioned.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the accompanying drawings, wherein is illustrated the preferred but obviously not necessarily

the only form of embodiment of the invention;

Figure 1 is a perspective view of an assembled pulsator unit embodying the present invention.

Fig. 2 is a top plan view partly in section of the assembled pulsator.

Fig. 3 is a top plan view of the body of the unit with the operating parts removed and disclosing the relative locations of various ports and passages.

10 Fig. 4 is a vertical sectional view on line 4—4 of Fig. 2.

Fig. 5 is a side elevation, partly in section, on the line 5—5 of Fig. 2.

15 Fig. 6 is a detail plan view of the control valve operating and timing means.

Fig. 7 is a detail plan view of the pulsator valve.

Fig. 8 is a detail sectional view on line 8—8 of Fig. 3.

20 Fig. 9 is an end elevation of one of the piston heads and cylinder on line 9—9 of Fig. 5.

Fig. 10 is a detail sectional view illustrating a modification of the piston construction.

Like parts are indicated by similar characters of reference throughout the several views.

25 The present pulsator unit embodies a main body or base 1, the top of which affords a valve table, and on opposite sides of which are mounted piston chambers 2—2. The lateral piston chambers 2 are vertically flattened into oval interior cross-sectional form, as shown in Fig. 9, and segmental external transverse contour, as appears in Fig. 1 and also Fig. 9.

30 Mounted for reciprocation within the laterally disposed chambers 2—2 are pistons 3, which are rigidly interconnected with each other for unison to and fro motion by intermediate relatively spaced connecting bars 4—4. The pistons are actuated by fluid pressure simultaneously admitted to one chamber 2 and exhausted from the other chamber. Each chamber 2 is provided with an inlet and outlet passage 5, communicating with the chamber beyond the piston head 3 when the latter is in its advanced position. These passages

35 5 in the walls of the chambers register with and form continuations of passages or bores 6—6 in the main body or base 1. The passages or bores 6 are provided with relatively spaced ports 7 in the top or valve table of the base. Intermediate the ports 7 is a port 8 which communicates

40 45 through a vertical passage 8' with exhaust chamber 10 within the base or body 1.

The pulsator unit is preferably, although not necessarily, mounted on the lid of a milk receptacle or other vessel or container, as illustrated

50 55 in copending application for Letters Patent, Serial

No. 316,602, filed January 31, 1940, which has issued as Patent 2,340,297 dated February 1, 1944, with which the exhaust chamber 10 communicates. Leading from the chamber 10, interiorly of the base 1, is an exhaust conduit 9 and fitting 11 to be connected through a hose with a pump or vacuum chamber. To control the ports 7 and 8 by interconnecting the exhaust port 8 alternately with the respective ports 7 and opening the other port 7 to atmosphere, there is pivoted at 12 to the top of the body or base 1 an oscillatory valve carrier 13.

Loosely positioned in a recess in the underside of the valve carrier 13 is an inverted cup-shaped valve 14, which rests by gravity upon the valve table and slides to and fro in hermetically sealed contact therewith as the valve carrier is oscillated. The recess of the valve 14 is of sufficient size that, when the carrier is at one limit of its range of movement, the valve encloses the port 8 and one only of the adjacent piston chamber ports 7, as illustrated in Fig. 6. At such time, the other port 7 is open to atmosphere, as shown at the left in Fig. 6. Upon reversal of the valve carrier about its pivot 12, the exhaust port 8 is interconnected with the piston chamber port 7 which was previously exposed.

The covered port 7 being thus placed in communication with the exhaust port 8, through the recessed interior of the valve 14, the air within the corresponding piston chamber 2 is exhausted through the passages 5 and 6 and port 7, thence beneath the valve 14 to the port 8 and through the vertical passage 8' to the exhaust chamber 10, with which a vacuum pump is connected through the conduit 9 and fitting 11. During the same operating period, air at atmospheric pressure is permitted to enter the opposite piston chamber 2 through the exposed port 7 and communicating passages 6 and 5 to force the interconnected pistons toward the exhausted or suction side of the unit. The rapidity of movement of the pistons in either direction and thereby the frequency of reversals or pulsations is governed by adjustment of a tapered plug valve 15 seated in the body 1 and intersecting the vertical passage 8' leading from the port 8. The plug valve has therein a notch 16 coincident with the passage 8'. By slight rotary adjustment of the plug valve, the capacity of the passage 8' may be varied. The valve 15 is provided with an adjusting head 17 and is held to its tapered seat under pressure of a spring 18 which bears upon the body of the plug valve.

It is quite necessary that the reversal of the valve carrier 13 be properly timed, and that its reversal be delayed until the end of the piston stroke, and then effected quickly with a snap-over action. For actuating the valve carrier, there is provided a rod 20 carried by the pistons 3 intermediate the parallel connecting bars 4. The valve carrier 13 is formed with a tail 21 which extends across the rod 20, as shown in Figs. 2 and 6. Loosely mounted on the rod 20 at opposite sides of the valve carrier tail 21 is a pair of thrust collars 22, and surrounding the rod intermediate the collars and piston heads is a pair of helical springs 23. As the pistons move to and fro under influence of fluid pressure in the piston chambers 2, one or the other of the springs 23 is compressed and the reaction of the spring is exerted against the tail 21 of the valve carrier 13 to oscillate the latter on its pivot 12. However, the reversal of the valve carrier is delayed until

the spring 23 is fully compressed, in order that it may transmit full, quick operating movement to the valve carrier. To this end, the opposite and broader end of the valve carrier 13 is formed with two arcuate indentations 24, each of which is concentric with the stud 25 when the valve carrier is at one or the other limit of its range of oscillatory movement.

Pivoted upon the screw stud 25 and projecting within the concentrically disposed indentation 24 of the valve carrier, is an oscillatory stop finger 26. Connected to and movable with the stop member 26 is a small gear sector 27. That illustrated in the drawings possesses but two gear teeth. However, additional and smaller teeth may be provided on such sector 27. Carried by one of the connecting bars 4 is a gear rack 28 with which the gear sector 27 intermeshes. As the pistons are reciprocated to and fro, carrying with them the gear rack 28, the gear sector 27 is correspondingly rocked within one or the other of the arcuate indentations 24. During such movement, one thrust collar 22 has been pressed against the tail 21 of the valve carrier and the corresponding spring 23 has been compressed. The valve carrier is held, however, against movement by the stop 26 until the latter has been moved beyond the engaged arcuate indentation. When the stop member 26 moves beyond the then concentric arcuate indentation, the spring 23 being under strong compression reacts to oscillate the valve carrier 13 on its pivot 12 to shift the valve 14 into overlapping relation with the previously exposed port 7 and to expose the previously overlapped port 7, and to simultaneously present the other arcuate indentation 24 in concentric relation with the center 25 of oscillation of the stop member 26. The reversal of the valve effects reversal of the exhaust and fluid pressure influences on the respective pistons, and, as the latter effect a return movement, the cycle of operation is repeated but in reverse direction.

The primary purpose of such alternating movement of the pistons 3 within the chambers 2 is to alternate a pulsator valve 29, which is loosely carried in an enlargement 30 of one of the piston connecting bars 4 and which rests upon and slides to and fro on a plane surface 31 of the valve table. In the valve supporting surface 31 are two relatively spaced ports 32, each of which communicates with separate passages 33 in the body or base 1, with which are in turn connected hose connecting nipples 34.

Instead of the usual Y connections, the fittings 34 are shown provided with approximately parallel branches 35 which are turned in opposite directions. This has been found to be a most convenient arrangement for coupling the air conduits of teat cups of a milking apparatus. Intermediate the ports 32 is a passage 36 which communicates with the exhaust chamber 10 in the body or base 1. As the piston reciprocates, the valve 29 is shifted to and fro to alternately connect each of the ports 32 with the exhaust passage 36 and simultaneously open the other port 32 to atmosphere. By so doing, the passages 37 and corresponding hose fittings 34 are alternately connected with the exhaust or vacuum pump and opened to admission of air, by which a pulsating effect is transmitted to connected teat cups or to other intermittent fluid pressure apparatus.

The operating parts exposed in Fig 2 intermediate the piston chambers 2 are enclosed be-

neath a removable housing or cover 38, shown in Fig. 1. To enable the pistons to be maintained sufficiently tight within the chambers 2, the piston head is formed in two separable flanged parts 39 and 40 divided transversely, as shown in Figs. 5 and 9. The part 39 is fixedly secured to the terminal head 41 of the connecting bars 4. The complementary part 40 is adjustable relative to the first part 39 against the tension of interposed helical springs 42. Such two-part flanged head is enclosed within a cup leather 43, which is clamped between the two-piece head 39-40 and a disc 44. The margins of the cup leather are expanded into close contact with the walls of the oval or elliptical chamber 2 by the expansion of the springs 42. In Fig. 10 is illustrated an alternative piston head assembly, wherein the inner flanged head 45 is formed with a peripheral rabbet 46. Seated in the rabbet is an annular helical spring 47, over which the cup leather 43 is disposed. The helical spring supports the margin of the cup leather and yieldingly holds it in conformity with the oval interior walls of the piston chambers.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While, in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described our invention, we claim:

1. A pulsator apparatus, including a support, a pair of oppositely disposed non-circular fluid pressure piston chambers carried thereby, corresponding non-circular reciprocatory pistons therein, an alternating valve controlling the admission and escape of fluid pressure to and from the respective chambers, a locking member for temporarily holding the valve in adjusted position and operative to release the valve for reverse movement as the pistons approach the limit of their movement in either direction, an oscillatory toothed segment moving in unison with the locking member, a reciprocatory rack bar moving in unison with the reciprocatory pistons and with which the toothed segment intermeshes, and transmitting to and fro motion thence to the locking member, a rod interconnecting the pistons, a pair of helical springs surrounding the rod in axially spaced relation and alternately tensioned by the to and fro movement of the pistons to actuate the alternating control valve when released by the locking member, and a pulsator valve actuated to and fro by the movement of the pistons.

2. In a pulsator mechanism, a pair of oppositely disposed fluid pressure chambers, reciprocatory pistons therein, a reciprocatory bar interconnecting the pistons for unison alternating motion, an alternating spring actuated valve controlling the admission and escape of actuating fluid under

pressure to and from the fluid pressure chambers, a movable stop for temporarily holding the valve against movement, an oscillatory gear sector operatively connected with the valve stop, and a rack bar on the reciprocatory piston connecting bar with which the gear sector intermeshes and to which alternating oscillatory motion is transmitted by the to and fro reciprocatory motion of the rack bar in unison with the movement of the pistons, the construction and arrangement being such that the stop is moved by the gear segment to intermittently release the valve for movement first in one direction and then in the other direction to permit the entrance and escape of fluid under pressure to and from the fluid pressure chambers alternately.

3. In a pulsating mechanism, a main frame, a pair of fluid pressure chambers carried thereby, reciprocatory pistons in the respective chambers, a connecting rod joining the pistons for unison to and fro motion, a pivotally mounted valve member controlling the admission and escape of fluid under pressure to and from the respective chambers, a pair of actuating springs disposed upon opposite sides of the pivotally mounted valve member and alternately tensioned by the movement of the pistons to actuate the valve first in one direction and then in the other, a stop member for preventing movement of the valve member, a toothed member connected with the stop member and an intermeshing toothed member movable with the pistons for adjusting the stop member to release the valve member for movement under influence of the springs as the pistons approach the limit of their range of movement in alternate directions.

4. In a pulsating mechanism, a main frame, a pair of oval fluid pressure chambers carried thereby, reciprocatory oval pistons within the fluid pressure chambers comprising relatively adjustable members subjected to spring pressure engagement with the fluid pressure chambers, interconnecting means joining the oval pistons for unison motion in alternate directions, a control valve for controlling admission and escape of actuating fluid to and from the respective fluid pressure chambers, timing means governing the operation of the control valve in timed relation with the movement of the pistons, and a pulsator valve operated by the movement of the pistons to alternately permit and arrest flow of fluid under pressure through an associated conduit, the construction and arrangement being such due to the ovalness of the fluid pressure chambers and the pistons therein that the overall height of the assembly is minimized.

5. In a pulsator mechanism, a main frame, horizontally disposed fluid pressure chambers carried thereby, said fluid pressure chambers being of greater width transversely of their axis in a horizontal plane than their vertical extent, corresponding oval reciprocatory pistons therein interconnected for unison travel motion in alternating directions, a control valve governing the admission and escape of fluid under pressure to and from the respective chambers, stop means therefor, rack and pinion control means associated therewith and actuated by the alternating travel motion of the interconnected pistons and a pulsator valve governing the flow of fluid under pressure through an associated conduit actuated by the movement of the pistons, the construction and arrangement being such that the overall height of the assembly is minimized.

6. In a pulsator mechanism for milking ma-

chines, a main frame, a pair of oppositely disposed vertically flattened oval fluid pressure chambers carried thereby, corresponding eccentric spring expanded pistons within the chambers comprising a pair of relatively adjustable members subjected to spring pressure engagement with the fluid pressure chambers, a tie member interconnecting the pistons for unison to and fro motion, a control valve governing the admission and escape of fluid under pressure to and from the respective chambers, and a pulsator valve controlling the flow of fluid under pressure through an associated conduit actuated by movement of the pistons, the construction and arrangement being such that the overall height of the assembly is minimized by the vertical flattening of the fluid pressure chambers.

7. In a pulsator mechanism, a main frame, a pair of oppositely disposed recessed extensions of substantially segmental exterior contour having relatively flat bottoms and arcuate tops carried thereby, a single fluid pressure chamber of less height than width within each recessed extension in non-parallel relation with the exterior contour thereof, whereby thickened wall portions are formed substantially coincident with the junctures of the bottom and sides of the recessed segmental extensions, passages in said thickened wall portions through which fluid under pressure is admitted to and permitted to escape from the chambers, corresponding oval pistons enclosed within the chambers and interconnected with each other for unison to and fro motion, a control valve governing the flow of actuating fluid to and fro through the passages in accordance with the movement of the pistons, and a pulsator valve actuated by the movement of the pistons to control the flow of fluid under pressure through an associated conduit, the construction and arrangement being such that the overall height of the assembly is minimized.

8. A fluid pressure receiving member for a pulsator mechanism comprising a hollow segmental body of substantially plano-convex form, an oval chamber therein, thickened wall portions substantially coincident with the juncture of the flat and convex faces of the body, and a passage in one of said thickened wall portions and communicating with the chamber through which fluid under pressure may be admitted to and exhausted from the chamber.

9. In a milking machine, a fluid pressure receiving member for a pulsating mechanism comprising a body of less height than width, a single oval fluid pressure receiving chamber therein, and a passage in the wall thereof through which fluid under pressure may be admitted to and exhausted from the chamber, the construction and proportions being such that the height of the member is minimized in proportion to the capacity of the chamber.

10. In a pulsator mechanism for milking machines, a main frame, oppositely disposed recessed

extensions carried thereby, the vertical dimensions of which are materially less than the horizontal dimensions thereof, a single oval fluid pressure chamber in each extension, with its major axis horizontally disposed, corresponding oval pistons in said chambers comprising a pair of relatively adjustable members maintained in engagement with the fluid pressure chambers under spring pressure, said pistons being interconnected for unison to and fro motion, a valve controlling the admission and escape of fluid under pressure to and from the chambers alternately, and a pulsator valve controlling the flow of fluid under pressure through an associated conduit actuated by the movement of the pistons, the construction and arrangement being such that the overall height of the assembly is minimized.

11. In a pulsator mechanism, a main frame, oppositely extending fluid pressure chambers carried thereby, reciprocatory pistons in the chambers interconnected for unison to and fro motion, a movable control valve governing the admission and escape of fluid under pressure to and from the fluid pressure chambers alternately, timing means for the valve including a stop preventing movement of the valve until the pistons approach the limit of their range of travel in one direction or the other, an oscillatory toothed segment connected with the stop, and a reciprocatory toothed member having intermeshing engagement with the toothed segment and reciprocated by movement of the pistons to transmit movement to the stop by which the control valve is released as the pistons reach the limit of their travel motion in each direction.

12. In a pulsating mechanism, a main frame, a pair of oppositely disposed fluid pressure chambers carried thereby, reciprocatory pistons therein interconnected for unison to and fro motion, a rod connecting the pistons, a pair of helical springs surrounding the rod, a control valve governing the admission and escape of fluid under pressure to and from the chambers, including an arm extending intermediate the pair of helical springs and against which the springs are alternately pressed by the pistons to compress the springs, the reaction of which serves to move the valve, stop means normally resisting the movement of the valve against the influence of the tensioned spring and spring engaging piston until the pistons approach the limit of their travel motion, intermeshing toothed members connected respectively with the stop and with the pistons for withdrawing the stop and releasing the valve for movement under reactive influence of the tensioned spring when the pistons have reached the limit of their travel motion in one direction, and a pulsator valve actuated by the movement of the pistons and controlling the flow of fluid under pressure through an associated conduit.
